UNITED STATES PATENT OFFICE

1,986,079

MARKING AND PUNCTURING TOOL

Felix F. Steiner, Santa Cruz, Calif.

Application April 11, 1933, Serial No. 665,616

4 Claims. (CL. 107—51)

The present invention relates to improvements in marking and puncturing tools, and constitutes an improvement over the measuring and puncturing tool, described in my application Serial No. 618,377, filed June 20, 1932. While the latter tool was principally intended for marking an object at evenly spaced points and for similarly puncturing objects such as bakery goods, it is the idea of the present invention to allow an operator to draw a series of parallel lines over the object in evenly spaced relation with means for uniformly increasing or decreasing the spacing when desired.

More particularly it is the object of the present invention to improve upon the measuring and puncturing tool previously described by adding suitable means for allowing lines of a desired depth to be drawn in parallel relation over an object.

It is further proposed in the present invention to utilize the free ends of the puncturing bars previously described to be used for the additional feature of this invention so that the same tool may be used for marking and puncturing when in one position, and for drawing parallel lines when in a reversed position.

It is further proposed in the present invention to provide suitable means in the line drawing arrangement for steadyng the hand of the operator, and for facilitating the drawing of straight lines.

It is further proposed in the present invention to arrange my improvements in such a manner that the entire bar may be stamped out of one piece, and the means for drawing lines may be obtained by mere bending of portions of said blank.

Further objects and advantages of the present invention will appear as the specification proceeds.

The preferred form of my invention is illustrated in the accompanying drawing in which

Figure 1 shows a side view of my tool in contracted condition;

Figure 2 is a similar side view of the tool in expanded position;

Figure 3 a detail view in side elevation of a single marking bar used in my tool;

Figure 4 an end elevation of the same marking bar; and

Figure 5 a side elevation of the blank out of which a marking bar is made.

While I have shown only the preferred form of the invention I wish to have it understood that various changes or modifications may be

made within the scope of the claims hereto attached without departing from the spirit of the invention.

Referring to the drawing in detail it will be seen particularly from Figure 2 that a plurality of links 1 are pivotally connected at their centers as at 2, and at their upper and lower ends as at 3 and 4 so as to form a set of lazy tongs. A plurality of bars 5 are pivotally connected to the pivots 3 in any suitable manner, and are formed with slots 6 in which the pivots 4 are made to ride, the latter pivots being preferably formed with heads 7 which hold the pivots in the slots. In this manner the bars 5 are arranged in parallel relation, and are evenly spaced from one another, and the spacing between the bars may be uniformly adjusted by contraction or expansion of the lazy tongs. The two end bars marked 5¹ and 5² are provided with suitable flanges 8 by means of which the manipulation of the device is facilitated. For holding the lazy tongs and the bars in adjusted position, I provide a cross bar 9 pivoted to the end bar 5¹ as shown at 10, and swingable alongside of the other bars.

The transverse bar 9 is provided with a number of teeth 11 in the bottom face thereof, and these teeth are adapted for engagement with a pin 12 projecting from the second bar 5, so that when any set of teeth engages with the pin 12 the lazy tongs are held in adjusted position. The opposite end member 5² has a slot 13 in the upper end thereof in alignment with the swinging plane of the transverse bar 9 so that when the entire device is in the contracted position shown in Figure 1 the transverse bar 9 is accommodated in the slot, and a set of teeth of the transverse bar engage with the bottom of the slot for holding the bars in assembled relation.

The bars 5 are all of the same length and project beyond the pivots 4 and are pointed as shown at 14 so that they may be used as puncturing tools in the manner described in the previous application.

In the present application the principal novel feature resides in the means for drawing straight lines arranged on the opposite ends of the bars 5. For this purpose the latter bars which are preferably made of a thin sheet of metal as indicated in Figures 4 and 5, are provided with a disc 15 arranged to revolve in a transverse plane, and with a blade section 16 arranged in the same plane as the disc, the blade section 16 having a cutting edge 17, arranged at a slight angle to the horizontal plane when the bar is in a vertical position, and projecting slightly beyond the

disc so that an extension of the cutting edge would just clear the disc as indicated by the dotted line 18. The blade section 16 which is preferably made of the same thickness as the disc 15 is arc-shaped adjacent the disc as shown at 19, and is provided with a second cutting edge 20 facing away from the disc so that the second cutting edge may be used without the disc becoming active.

10 The bar 5 is preferably made out of the blank shown in Figure 5 which shows two arms 21 projecting from the bar near one extremity thereof in slightly inclined direction, while the blade section 16 forms the extremity of the bar 5 and is connected thereto by a neck portion 22. For changing the blank into the desired tool, it is merely necessary to twist the blade section 16 at its neck portion so that it forms a right angle with the plane of the bar 5, and to turn the two arms 21 at right angles to the bar so as to serve as supporting members for the journal 23 on which the disc 15 is mounted. The disc may be formed with a suitable hub portion 23' so as to insure proper centering relative to the arms 21.

25 The operation of the device may be easily understood from the foregoing description. If the device is to be used as a puncturing tool, it is preferably employed in its contracted position as shown in Figure 1 so that a person may take hold of the device with one hand, and puncture the object by successive applications. If the tool is to be used as a mere marking tool, that is for establishing uniformly spaced points on an object, the tool may be used in the form shown 30 in Figure 2 with the two end members spaced from one another so as to span the entire object, and the device locked in position by the bar 9. Pressing down of the points 14 into the object will define the desired marks. If it is desired to 35 draw a series of parallel lines over an object or to groove the object, or even cut the same along parallel lines, the upper structure of the bars 5 is used.

First the device is again adjusted so that the 40 end bars span the entire width thereof, and then the discs 15 are pressed into the object; then the entire device is drawn over the same so that the discs draw parallel lines of the desired spacing across the object. These lines may be in the 45 nature of grooves, if a grooving of the object is desired, or may even cut through the object if such is the desired effect. The blades 16 follow

the grooves made by the discs, and they may be used for the purpose of deepening the groove by suitable tilting of the instrument. The blades serve the further purpose of steadyng the hand of the operator, since they ride in the grooves made by the discs, and thereby hold the discs to a straight line. If for certain purposes the discs cannot be used to advantage the operator may turn the device around and use the cutting edges 20 of the blade.

10 I claim:

1. In a tool of the character described, a plurality of marking bars, means for supporting the same in a single plane in evenly spaced relation with freedom of uniformly increasing and decreasing the spacing, sets of ears projecting transversely from the bars near the ends thereof, discs revolvably supported between the ears in transverse relation to the bars and offset from the plane thereof, and guide blades formed integral with the bars and projecting transversely from the plane of the bars in an opposite direction and in trailing relation to the discs.

2. In a tool of the character described, a plurality of marking bars, means for supporting the same in evenly spaced relation with freedom of uniformly increasing and decreasing the spacing, and guide blades arranged in registering ends of the bars and in transverse relation thereto, the guide blades being formed integral with the bar 30 and being twisted in transverse direction.

3. A blank for a marking bar of the character described comprising a flat bar having arms extending therefrom in opposite directions near one extremity thereof, and having a blade section at 35 said extremity and a neck portion connecting the blade section and the bar so as to allow the blade to be turned at right angles to the bar by twisting the neck portion and to allow the arms to be bent at right angles relative to the bar so as to form a 40 bearing for a disc to be alined with the blade section.

4. A marking bar of the character described having a blade section at one extremity thereof, a neck connecting the bar and the blade section 45 and being twisted to present the blade section transversely to the bar, a cutting edge on the blade section being slightly inclined and a disc revolvably supported in alignment with the blade section, the circumference of the disc stopping short 50 of the cutting edge line.

FELIX F. STEINER.
